PULP SCREEN

Henry William Downs, Lennoxville, Quebec,
Canada

Application February 23, 1939, Serial No. 258,065

1 Claim. (Cl. 92—30)

This invention relates to improvements in a pulp screen plate fastener. Its primary object being to devise and construct means to secure pulp screen plates in the screening vats. Said means being adaptable for rapid changing of the screens thereby reducing the loss of time required for this purpose to a minimum.

A further object of the invention is to provide a screen plate fastening device having means to prevent leakage of the pulp material around the sides.

Another object of the invention is to provide a screen plate fastener adaptable to screen plates of reduced thickness. Said screen plates being more efficient to allow the pulp material to flow through more freely. The fastener as herein constructed will prevent vibration of the screen plates thereby permitting use of the thin screen plates made from high grade metals at low cost.

With these and other objects in view that may appear while the description proceeds the invention resides in the novel construction and arrangement of parts as hereinafter more specifically set forth, claimed and shown in the accompanying drawings forming part of this application and in which:

Fig. 1 is a plan view of a vat having the screens secured therein by my improved screen plate fastener.

Fig. 2 is a side view of the same.

Fig. 3 is an end view of the open end.

Fig. 4 is an end view of the closed end.

Fig. 5 is an enlarged sectional view showing details of the fastener.

Fig. 6 is a sectional view at right angles to that shown in Fig. 5.

Referring more in detail to the drawings wherein similar reference characters designate corresponding parts throughout the several views it will be seen the invention comprises a support or vat frame 10 preferably of wood on which screen frames 11 are secured by bolts 12 and washers 13. Said screen frames are adapted to be joined together to accommodate any number of screen plates as each frame normally accommodates four screen plates.

The frame joint is shown in detail in Fig. 5, wherein it will be seen the ends 14 are bolted together by bolts 15 and a key 16 is provided to engage keyways 17 in each end member to ensure correct alignment and to prevent any movement. It will be seen the frame has a number of transverse bars 18 in each of which is a longitudinal slot 19 wherein the downwardly turned ends 20

of the screens 21 are placed and a small strip of felt 22 or similar material placed in the bottom thereof.

In the drawings a vat is shown having an open end and a closed end. In the former a plate 23 is screwed to the frame 10 and bears against the end of the screen plate. The key 16 engages a key-way 17 and a corresponding key-way in the said frame 10.

The closed end construction is provided with 10 the sealing or tightening which consists of a sealing strip 24 which extends the width of the vat. Said sealing strip has a lower bearing edge 25 having a longitudinal slot 26 for felt or similar packing material. This bearing edge engages 15 the screen plates 21 and clamps them against the screen frame 11. The strip is arranged to accommodate a locking nut 27 behind the face 28 and a locking bolt 29 threadably engages the same. Said bolt is constructed with a collar 30 20 which bears on the top edge of the sealing strip while the bolt passes through an aperture 31 provided therefor. The nut 27 has a lip 32 which engages a slot 33 in a locking plate 33a. Said locking plate is positioned vertically between the 25 screen frame 10 and sealing strip 24, and the support frame 10, and is secured to the latter by screws 34. On the lower end of the locking plate is a right angled projection 35 which engages the key-way 17 of the frame 11 and anchors the plate thereto. In this manner it will be seen that as the bolt is turned the pressure is applied below and above the screens thereby preventing any leakage of the pulp material past the joint.

Side sealing strips 36 are provided and are constructed similarly to the end strip. The locking bolt, nut and plate are similar and operate in the same manner as the end sealing device and therefore need not be described in detail.

From the foregoing description it will be seen that the disclosure is not limited in any way to number or size of screen plates or to the detailed construction of the same providing the ends are designed to fit the screen frames. It will also be apparent that the screens may be readily removed by loosening the device as the sealing strips may be detached entirely when the nut is loosened sufficiently to disengage the lip 50 32 from the slot 33 and the screen plates may then be lifted directly from the screen frames.

It is believed that the construction and advantages of the structure shown may be apparent from the foregoing paragraphs taken in con-

junction with the accompanying drawings without further detailed description.

While the preferred embodiment of the invention has been disclosed it is understood that minor changes in the details of construction, combination and arrangement of cooperating elements may be resorted to within the scope of what is claimed without departing from the spirit of the invention.

10 I claim:

A pulp screen comprising a vat frame, screen plate frames adapted to be secured together end to end, means securing the same to the vat frame, key-ways formed transversely in the adjoining 15 faces of the frame and a key engaging said key-ways where two frames are joined, screen plates having turned down edges forming flanges, channel bars extending transversely of the screen plate frames adapted to receive the flanges of 20 adjacent screen plates in meeting relation, a

packing strip in the bottom of said channels bridging the joint between the flanges of the screen plates, sealing strips arranged to engage the upper surface of the screen plates, said sealing strips having a lower bearing surface arranged to bear on the upper surface of the ends of the screen plates, a locking plate positioned between the sealing strip, screen plate frame, and the vat frame to which it is secured, said locking plate having a transverse projection on 10 the lower end engaging the transverse key-way in the screen plate frame, a locking nut having a projecting lip thereon, said lip engaging an aperture in the locking plate to bear upward on the same, a bolt having a collar below the 15 nut thereof and lug arranged to bear on the sealing strip as the device is tightened, substantially as set forth.

HENRY WILLIAM DOWNS. 20
